UNITED STATES PATENT OFFICE.

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK.

WINDOW-SASH AND HOLDER.

1,248,785.

Specification of Letters Patent. Patented Dec. 4, 1917.

Application filed October 4, 1917. Serial No. 194,708.

To all whom it may concern:

Be it known that I, Roy T. Axe, a citizen of the United States, and a resident of Syracuse, in the county of Onondaga and 5 State of New York, have invented a certain new and useful Window-Sash and Holder, of which the following is a specification.

This invention relates to window sashes particularly metal sashes for railway cars 10 and the like, in which the sash rails and stiles are narrow compared with the broad surfaces of the usual wood or metal rails and stiles of window sashes, and it has for its object a particularly simple and efficient arrangement of the casing of the sash holder or lock on the narrow rails and stiles of the 15 sash whereby the mechanism of the holder is concealed and the casing presents a finished appearance from both sides of the 20 sash. Heretofore, the mechanism of the holder or the inner face of the casing lapsing the sash has been visible through the pane and presents a more or less unfinished appearance.

25 In describing this invention, reference is had to the accompanying drawing in which like characters designate corresponding parts in all the views.

Figures 1 and 2 are opposite fragmentary 30 elevations of a corner of a sash embodying my invention.

Fig. 3 is a sectional view on line 3—3, Fig. 1.

Figs. 4 and 5 are opposite face views of 35 the detached sections of the casing of the sash holder.

This window comprises a sash and a holder or lock located at one or both lower corners of the sash and comprising a casing 40 composed of complementary opposing sections which are opposed to opposite faces of the pane, and movable holding means carried by one section on the side thereof opposed to the other section.

45 1 designates the sash which comprises hollow sheet metal rails 2 and stiles 3 which are shaped to form a channel 4 in which the margin of the pane 5 extends, a packing 6 of resilient material being interposed between the margin of the pane 5 and the 50 walls of the channel 4.

7 and 8 are sections of the sash holder casing, and 9 is a detent associated with the section 7 and located at the edge of the sash 55 in position to coact with a rack not shown

or other device or the window frame to resist movement of the sash upwardly and downwardly in the window frame, the sash being generally acted upon by a spring roller or other device tending to lift the 60 same as will be understood by those skilled in the art.

The detent 9 is here shown as mounted upon a rock shaft 10 journaled in the bearing 11 carried by the section 7 of the casing 65 at the edge thereof and extends into a recess 12 in the section 7, the rock shaft having a finger or pinch lever 13 mounted on its inner end, which lever extends through the front side of the section 7 and has a handle 70 14 at its outer end opposed to a grip handle 15 projecting from the outer face of the section 7.

The shaft 10 is rocked by the lever 13 against the action of a spring 16 coiled about 75 said shaft and having one end fixed in any suitable manner to the section 7 of the casing at 17, and being connected at its other end to the shaft 10, it being here shown as connected to the hub of the lever 13. The 80 outer end of the shaft 10 and the detent and also the outer portion of the bearing 11 for the shaft extends into the hollow portion of the stile, the bearing 11 having the front portion of its outer end cut away and flush 85 with the face of the stile and the detent 9 moves out of a slot 18 formed in the front wall of the stile.

The section 7 of the casing has flanges 90 20 which lap the front faces of the rail and a stile of the sash and which are secured thereto in any suitable manner as by screws 21. The shaft 10 and spring 16 are supported by the portion of the section 7 which is opposed to the pane 5 and hence would ordinarily be visible through the pane. However, the inner side of the section 7 and the mechanism carried thereby are concealed by the section 8 of the casing which is complementary to, and of the same shape and extent as the portion of the casing 7 opposed to the panel 5. The section 8 thus forms a cover for the section 7 and both form a complete casing for the lock mechanism. Heretofore, the mechanism has either been exposed or a cover plate for the mechanism of the lock has been secured to the section 7 between the inner face of said section and the pane, but such a construction in addition to requiring provision for securing the cover 105 110

plate in position presents an unfinished appearance through the pane.

The section 8 is here shown as formed with flanges 22 projecting from the vertical and horizontal margins thereof which flanges extend around the edge of the pane or the packing 6 thereof in the channel 4. It is also formed with a flange or lip 23 on its top margin which engages the face 10 of the pane and thus prevents dirt and water especially during washing of the window from entering the corner of the sash.

The vertical and horizontal margins of the section 8 with the flanges 22 enter the 15 channel in which the margin of the pane is located, as seen in Fig. 2, and hence the section 8 is held in position by the pane 4, the flanges 22 preventing withdrawal of the section 8. No additional fastening means 20 are required to hold the section 8 in position or to secure it to the section 7.

This casing is particularly advantageous in that it completely conceals the sash holding mechanism and is readily and economically applied to the window sash, it being understood that the sash locks are furnished to the car companies for application to the window sashes.

What I claim is:

30 1. In a window, the combination of a sash and a holder at the corner of the sash comprising a casing including two sections arranged opposite to each other on opposite sides of the pane of the sash, and movable holding means supported in one section on the side thereof opposed to the pane, and the other section being arranged to conceal said mechanism, substantially as and for the purpose described.

40 2. In a window, the combination of a sash and a holder at the corner of the sash com-

prising opposing sections complementary to each other and arranged at the corner of the sash on opposite sides of the pane, the sections having portions opposed to opposite 45 faces of the pane, and movable holding means carried by one section on the side thereof opposed to and opposite to the other section, substantially as and for the purpose specified.

50 3. In a window, the combination of a sash and a holder at the corner of the sash comprising opposing sections complementary to each other, the sections being arranged at the corner of the sash on opposite sides of 55 the pane, movable holding means carried by one section on the side thereof opposed to the pane and opposite to the other section, the former section having means lapping the sash and secured thereto and the latter 60 section having means extending around the edge of the pane, substantially as and for the purpose set forth.

4. In a window, the combination of a sash and a holder at the corner of the sash comprising opposing complementary sections arranged in the corner of the sash on opposite sides of the pane and movable holding means carried by one section and exposed on a side 65 thereof opposed to the pane, and the other section being of the same shape and extent as the former section and having the major part thereof spaced apart from the pane and being formed with a flange along its top edge, the flange extending toward and 70 engaging the pane, substantially as and for the purpose described.

75 In testimony whereof, I have hereunto signed my name, at Syracuse, in the county of Onondaga, and State of New York, this 26th day of September, 1917.

ROY T. AXE.
